UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

APPARATUS FOR CONNECTING GUN-CARRIAGES TO THEIR LIMBERS.

1,309,914.

Specification of Letters Patent. Patented July 15, 1919.

Application filed February 14, 1918. Serial No. 217,185.

To all whom it may concern:

Be it known that I, EUGÈNE SCHNEIDER, a citizen of the French Republic, resident of Le Creuzot, France, have invented a new 5 and useful Improvement in Apparatus for Connecting Gun-Carriages to Their Limbers, which is fully set forth in the following specification.

For the purpose of assuring elasticity in 10 the support and coupling of the trails or false trails of gun carriages to limbers for transporting gun carriages or parts of gun carriages, it has already been proposed to mount pivotally, on the limber or on the trail, an abutment which is movable on a 15 horizontal axis, either on the limber or on the trail, under the influence of an opposing spring carried by the limber or the trail.

Those known devices complicate the construction of the limber or of the trail; they necessitate extra strength in the parts; and they do not assure as regards vertical movements a constant elasticity in all the relative 20 positions of the trail and limber.

The present invention has for its object 25 to provide an improved construction for remedying these drawbacks.

According to the preferred embodiment 30 of this invention the elastic support of the trail or movable perch or false trail is provided by the limber (which remains unaltered in construction) on which is mounted a racer or track fixed rigidly thereto. The 35 real trail or false trail carries merely an elastic device provided at a suitable point near its end and adapted to rest on said racer, which device retains a constant elasticity irrespective of the point of the racer on which it bears, at any time, in the movements of the trail on the coupling pivot pin. The improved apparatus further assures an 40 elasticity of the coupling in all positions by providing, instead of the usual fixed eye by means of which the trail engages with the 45 pivot pin of the limber, an eye capable of moving in the direction of the axis of the trail, between two spring stops provided in or on the latter.

Two examples of embodiments of the 50 invention are illustrated on the accompanying drawings in which:

Figure 1 is a longitudinal side elevation of a movable perch or false trail for coupling a gun to a limber of the usual con-

struction, provided with the improved apparatus for giving to the combined gun and movable perch an elastic support upon and elastic coupling to the said limber. 55

Fig. 2 is a plan thereof.

Fig. 3 is a partial vertical section, drawn 60 to a larger scale, of the movable perch.

Fig. 4 is a side elevation partly in vertical section of a gun carriage trail coupled to a limber by means of a modified form of the 65 improved construction.

In the several figures, A is the axle and B, B, are the wheels of a limber of the usual construction, provided with a fixed racer or track C.

According to this invention the movable 70 perch or false trail D carries an elastic device that serves to support the said perch or trail elastically upon the fixed racer C. This elastic device may, as shown in detail in Figs. 3 and 4, comprise a fixed sleeve E engaged at the desired depth in the tail of the trail or perch or in the vicinity of the free end of the perch or trail. This sleeve is suitably retained upon the latter part as by means of a cap E¹ fixed thereon and serving as a 75 bearing for one end of a spring F, the other end of which bears upon the movable member G of the said elastic device which constitutes the support proper. This movable member G may take the form of a headed 80 sleeve suspended from a rod g, the free end of which is carried, by means of a nut g¹ and Belleville washers g², by the fixed bearing E¹ for the spring. 85

The coupling is effected in the usual manner by means of an eye H on the real trail or false trail slipped over the pivot pin I on the limber. But, according to the present invention, the said eye, instead of being fixed in the real trail or false trail, is movable 90 along the longitudinal axis of the latter in a buttonhole-shaped slot d. Elastic supports or bearings are provided between the movable eye H and two fixed abutments D¹, D² of the trail. The said supports or bearings 95 may each consist of a coiled spring J through which extends a guide rod K which is fixed to the eye H, and is capable of sliding in the corresponding abutments D¹, D². 100

It will be understood that this construction is very simple since it dispenses with the use of levers or rocking beams and all supports pivoted to the trail or to the limber, 105

while it has the additional advantage of assuring, both as regards the support and as regards the coupling, a constant degree of elasticity irrespective of the inclination or obliquity which the axis of the trail may assume relatively to the axis of the limber.

What I claim is:—

1. In combination with a trail, a limber and a coupling between the forward end of the trail and said limber, an elastic supporting member on said trail adapted to rest upon the limber for taking the weight of the trail.
2. In combination with a trail, a limber and a coupling between the forward end of the trail and said limber, an elastic supporting member on said trail adapted to rest upon the limber for taking the weight of the trail, said elastic supporting member comprising a movable element for engaging the limber, and a spring between said element and the trail.
3. In combination with a trail, a limber and a coupling between the forward end of the trail and said limber, an elastic supporting member on said trail adapted to rest upon said limber for taking the weight of the trail, said member moving with said trail relatively to said limber.
4. In combination with a trail and a limber, a pin on the limber, an eye movably mounted in a slot in the trail, and two spring abutments between said eye and trail whereby the reaction of the trail is transmitted elastically to the limber.
5. In combination with a trail and a limber, an elastic supporting member on said trail adapted to rest upon the limber for taking the weight of the trail, a pin and eye coupling between the trail and limber, and spring abutments between which said eye is movable.
6. In combination with a trail and a limber, an elastic supporting member on said trail adapted to rest upon the limber for taking the weight of the trail, a pin on the limber, an eye on the trail, said eye being movable in a slot in the trail, and two

spring abutments between the eye and the trail for taking the reaction of the trail.

7. In combination with a trail and a limber, a pin and eye coupling between said trail and limber, spring abutments between which said eye is movable, and an elastic supporting member on the trail adapted to rest upon said limber for taking the weight of the trail, said member moving with said trail relatively to said limber.

8. In combination with a trail and a limber, an elastic supporting member mounted on said trail and adapted to rest upon the limber for taking the weight of the trail, a pin on the limber, a movable eye on the trail, and one or more spring abutments between said eye and the trail for taking the reaction of the trail.

9. In combination with a trail, a limber and a coupling between the forward end of the trail and said limber, an elastic supporting member on one of the first two elements and bearing on the other of said elements for taking the weight of the trail, said member being bodily spaced from said coupling.

10. In combination with a trail, a limber and a coupling therebetween, a track on the limber, and an elastic supporting member on the trail resting on and slidale on said track for taking the weight of the trail.

11. In combination with a trail and a limber, a coupling between said trail and limber comprising a pin on one of said elements and an eye on the other of said elements, said coupling being bodily movable with respect to one of said elements, and spring abutments between said coupling and the last-named element for taking the reaction of the trail.

In testimony whereof I have signed this specification in the presence of two subscribing witnesses.

EUGÈNE SCHNEIDER.
